UNITED STATES PATENT OFFICE

ALEXANDER JAMESON, OF INDIANAPOLIS, INDIANA, ASSIGNOR TO F. R. HENSHAW,
OF INDIANAPOLIS, INDIANA, TRUSTEE.

CONTROLLER FOR AUTOMATIC MUSICAL INSTRUMENTS.

1,109,992.

Specification of Letters Patent.

Patented Sept. 8, 1914.

Application filed May 26, 1910. Serial No. 563,527.

To all whom it may concern:

Be it known that I, ALEXANDER JAMESON, a citizen of the United States, residing at Indianapolis, in the county of Marion and State of Indiana, have invented a new and useful Controller for Automatic Musical Instruments, of which the following is a specification.

At the present time player pianos or automatic player attachments for pianos are quite common and these devices have controlling levers by means of which their various mechanisms may be controlled in order to vary the speed of sound production, the force exerted upon the sound producing members, and so forth; but the levers or other members, by means of which such control is exercised are generally quite small and accessible only by a person seated at the instrument, so that a singer appearing in the usual position of performance before an audience would be unable to control the operation of the instrument.

The object of my present invention is to provide a mechanism by means of which an automatic musical instrument of the type described, or one especially constructed for use in connection with my invention, may be readily controlled from a distant point by means of an apparatus conveniently held in one hand of the controlling operator, the construction being such that the controlling operator may, while controlling the operation of the musical instrument, perform as a singer or other soloist.

The accompanying drawings illustrate my invention.

Figure 1 is a perspective view of an ordinary and common form of player piano equipped with my invention; Fig. 2 a detail in partial section and about full size of the controlling member of my apparatus and one of the lever-operating members, of an electrical type; Fig. 3 a view of a modified controlling apparatus actuated by air pressure; Fig. 4 an enlarged detail of one of the portions shown in Fig. 3 in connection with the controlling member therefor; Fig. 5 a view similar to Fig. 4 showing a modified electrical apparatus; Fig. 6 a view similar to Fig. 4 showing air-controlled lever-operating means and electrically-controlled valve mechanism for controlling the air-controlled members; Fig. 7 a sectional detail of a modified form in which the connection between

the controlling member and the lever operating member is an incompressible liquid, and Fig. 8 a section on line 8-8 of Fig. 7.

In Figs. 1 and 2 of the drawings, 10 indicates the musical instrument provided with a plurality of levers 11, 11 by means of which the different functions of the player mechanism may be controlled. Associated with each of the levers 11, so as to operate the same, is the core 12 of a solenoid 13. The coil of the solenoid 13 is divided into a plurality of sections by taps 14, 15, 16, 17, 18 and 19, as many sections being provided as may be desired, one for each desired position of the lever 11. The controlling member of my apparatus may be given any desired form but preferably one which can be readily grasped in one hand and I have therefore shown this member as composed of a main cylindrical casing 24 in which is mounted a plurality of plungers or finger pieces 25, one of these plungers being provided for each lever 11. The plungers of this controlling member will be modified in accordance with the particular type of apparatus which it is to control. In Fig. 2 each plunger 25 is mounted in a tube 27 arranged within casing 24 and provided at one side with an insulating strip 28 in which is mounted a plurality of electrically insulated terminals 29 which are connected by a suitable cable 31 with the different taps 14 to 19 inclusive of the coil of the solenoid 13. Plunger 25 carries a pair of terminal fingers 32 one of which is in continuous engagement with tube 27 and the other of which is adapted to be brought successively into contact with the terminals 29. A spring 34 serves to normally project each plunger to the position shown in Fig. 2. The several tubes 27 are connected to a return line 35 which is carried to one terminal of a suitable electric supply 36, the other terminal of said supply being connected by wire 37 with the terminal of the coil of the solenoid 13.

In operation the operator may, by projecting the desired plunger 25 into the controlling member 24, connect one or more of the sections of the coil of the corresponding solenoid 13 with the current supply and thus cause the core 12 to move into the coil a certain definite amount which will thus shift the corresponding lever 11 to the desired position so as to affect the player mechanism to the desired extent. As soon as the operating

plunger 25 is released the lever 11 will be returned immediately to its normal position by a suitable spring 91 in the ordinary manner. The several plungers 25 are arranged so as to be readily individually engaged by separate fingers of the hand of the operator so that the plungers may be independently controlled.

In the form shown in Figs. 3 and 4 I have provided an air cylinder 41 and piston 42 for controlling each lever 11, a spring 43 serving to normally project the piston in one direction. Leading from one end of cylinder 41 is a passage 44 connected to a suitable vacuum producer so that, when the machine is in operative condition, the vacuum produced within the cylinder 41 will serve to entirely overcome spring 43. Arranged adjacent cylinder 41 is a valve chamber 45 within which is mounted a valve 46 controlling a passage 47 which forms a communication between chamber 45 and cylinder 41.

Leading into valve chamber 47 is an air inlet 48. Leading into chamber 45 below valve 46 is a passage 49 which leads to a vacuum chamber. A spring 51 acts upon valve 46 to drive it to the position shown in the drawings. Leading from chamber 45 below valve 46 is an air passage 52 which leads to one of a series of chambers 53 formed in the casing 24' adapted to be held in the hand of the controlling operative, this casing 24' being very similar to the casing 24. Projectible into each chamber 53 is a plunger 25' which is normally held in the position shown by spring 54. The plunger 25' operates as a valve to normally prevent inflow of air into chamber 53 from atmosphere but said plunger is provided with an elongated opening 55 by means of which greater or lesser communication with the interior of the chamber 53 may be established.

In operation a desired vacuum is maintained in passages 49, 52 and 44 and cylinders 41 and chambers 53, this vacuum serving to draw valves 46 and pistons 42 to the positions opposite to those shown in Fig. 4. By pressing inwardly upon one of the plungers 25' to any desired extent any desired amount of inflow of air from the atmosphere into chamber 53 may be permitted. This air will flow through passage 52 into the lower end of the valve chamber 45 and thus reduce, to a greater or lesser extent, the vacuum in the lower end of said valve chamber so as to permit spring 51 to drive valve 46 upwardly so as to open passage 47 to a greater or lesser extent, thus permitting inflow of air through opening 47 into cylinder 41 and thus decreasing, to a greater or less extent, according to the distance the opening 47 is uncovered by the movement of the valve 46, the effect of the suction through passage

44, and thus permitting spring 43 to drive piston 42 to the left and to operate lever 11. As soon as plunger 25' is permitted to resume its normal position a vacuum is re-established in the chamber 53 and passage 52, valve 46 is drawn back so as to close opening 47, and a vacuum is again re-established in cylinder 41 so as to draw piston 42 back to its normal operating position.

In the construction shown in Fig. 5 the lever 11 is controlled by the core 12 of a solenoid 13 like that shown in Fig. 2. In this form the several sections 14, 15, 16, 17 and 18 of the coil of the solenoid are connected to terminals 14', 15', 16', 17' and 18' respectively of solenoid switches 14'', 15'', 16'', 17'' and 18'' respectively, the coils of which are in circuit with the terminals 29 of the hand piece 24, these terminals 29 being engageable by the terminals 32 of the plunger 25. A battery, or other source, 81 is connected by wires 82 and 83 with the solenoid coils and the terminals 14' to 18'. In this construction, whenever the proper plunger 25 is shifted so as to bring the terminals 32 in position to connect the desired one of terminals 29 the proper solenoid 14'' to 18'' is energized so as to close the proper switch 14' to 18', and thus energize the coils of solenoid 13 in such way as to produce the desired position of core 12 and the consequent desired position of lever 11. This construction permits the use of heavier currents in the solenoid than in the hand pieces.

The structure shown in Fig. 6 is a combination of the structures shown in Figs. 2 and 4. In this form the cylinder 41 has an air inlet 47 which is opened and closed to a greater or lesser extent by means of a valve 46' carried by a solenoid core 61. The position of this core is controlled by a multi-sectional coil 62 the different sections of which are connected to terminals 29 in the hand piece 24, each plunger 25 carrying terminals 32 which connect said terminals 29 as in the form shown in Fig. 2. A vacuum is normally maintained by means of passage 44 and a suitable pump (not shown).

In the construction shown in Figs. 7 and 8 the cylinder 41, piston 42 and spring 43 are like the same parts shown in Fig. 4 the vacuum being maintained in cylinder 41 through passage 44. The cylinder is provided with air inlets 47 and 48 controlled by valve 46''. The position of this valve 46'' is controlled however by an incompressible liquid, such as oil or water, 71 which is shifted through tube 72 from the hand piece 24''. In this form each finger plunger 25'' is provided with a piston head 73 mounted in a cylinder 74 formed in the hand piece and connected with one of the tubes 72. Each finger piece is normally

held outwardly by a suitable spring 75 and an inward movement of the finger plunger will tend to drive the liquid 71 through the apparatus in such way as to open valve 46" 5 against the action of the spring 46.

It will be readily appreciated from the above that my invention may assume a very large variety of forms without, however, departing from the fundamental feature of the 10 invention which consists in the provision of two devices, one of which comprises a multiplicity of members arranged in connection with the musical instrument in such way as to operate its controlling levers or 15 members, and the other of which consists of an apparatus which may be carried to a point distant from the musical instrument and there be manipulated by the operative.

I claim as my invention:

20 1. A manipulator for automatic musical instruments comprising a plurality of motors each having a movable member adapted to engage and operate a controlling member of the musical instrument and each comprising 25 means for establishing a multiplicity of positions of said movable member, and a controlling member, said controlling member comprising a plurality of independently movable members each capable of occupying 30 a multiplicity of positions, and means controlled by each of said last mentioned movable members in its multiplicity of positions for causing the movable members of the corresponding motors to occupy 35 the corresponding one of its multiplicity of positions.

2. A manipulator for automatic musical instruments comprising a plurality of motors each consisting of an air cylinder, a 40 piston mounted therein, and a valve variably positionable to variably control the flow to and from the cylinder; means carried by the piston for engaging and operating a controlling member of the musical instrument; 45 a hand-portable controller transportable to and from a point distant from the plurality

of motors and comprising a plurality of independently movable members, and intermediate connections between each of said independently movable members and a valve 50 of a motor for controlling the position of such valve.

3. The combination, with a musical instrument, mechanical means for automatically sounding the same, and a plurality of controller members capable of occupying a multiplicity of positions by which the operation of the mechanical automatic sounding mechanism may be controlled, of a hand-piece having a plurality of independently movable controlling members each capable of occupying a multiplicity of positions and intermediate connections between the several controlling members of the hand-piece 60 and corresponding controller members of the 65 musical instrument, whereby manipulation of the hand-piece member will control the operation of the instrument.

4. The combination, with a musical instrument, mechanical means for automatically sounding the same, and a plurality of controller members capable of occupying a multiplicity of positions by which the operation of the mechanical automatic sounding mechanism may be controlled, of a hand 70 piece having a movable controlling member capable of occupying a multiplicity of positions, and intermediate connections between the controlling member of the hand-piece 75 and corresponding controller member of the 80 musical instrument, whereby manipulation of the hand-piece member will control the operation of the instrument.

In witness whereof, I have hereunto set my hand and seal at Indianapolis, Indiana, 85 this twentieth day of May, A. D. one thousand nine hundred and ten.

ALEXANDER JAMESON. [L.S.]
